BILLIARD CUE LOCK

John Bowman, Elyria, Ohio

Application May 15, 1947, Serial No. 748,178

2 Claims. (Cl. 70—62)

1

My invention relates to improvements in billiard cues and relates more particularly to improved locking means therefor. My invention also can be adapted for use as improved locking means for fishing poles, flag poles, or as oar locks, etc., to secure same to a boat with which the same may be used, and various other uses may be found for the improved structure of my invention.

A principal object of my invention is to provide improved locking means for billiard cues whereby such cues may be securely locked in the racks within which the same are normally placed when they are not in use.

A further object of my invention is to provide means whereby the locking means may be associated with the cue without altering in any respect the basic conventional form of cue.

Another object of my invention is to provide cooperative means associated with billiard cue racks which will receive such improved cues, when desired, and individually lock each such cue in place in the rack so that only the owner of each cue may be able to remove his cue from the rack.

A further object of my invention is to provide improved means associated with a cue rack which are adapted to cooperate with locking means carried by a cue which will not alter in any respect the conventional form of billiard cue racks.

A still further object of my invention is to provide cooperating locking means on said cue and rack which will be simple in construction, economical in manufacture and high efficient in use.

Still further and other objects of my invention as applied to the billiard cue and racks, and the various other uses to which my invention can be put, will become increasingly apparent by reference to the following description and appended drawings to which reference will be had in the description, in which:

Fig. 1 is a front plan view of a billiard cue rack, showing certain cues having the associated cue lock of my invention positioned therein;

Fig. 2 is a vertical transverse view taken through the line 2—2 of Fig. 1;

Fig. 3 is a vertical transverse view taken through the line 3—3 of Fig. 1;

Fig. 4 is an enlarged fragmentary view of the cue locking means of my invention, certain portions being broken away to more fully illustrate the locking means;

Fig. 5 is a transverse sectional view of the cue locking mechanism of Fig. 4, certain portions being broken away for further clarification.

2

Referring now to the drawings, in all of which like parts are designated by like reference characters, at 10 I show a conventional type billiard cue having an adapter collar or spool-shaped adapter secured to the outer end of the cue, said collar comprising a disc shaped inner end portion 11 which is adapted to be secured to the outer face of the outer end 12 of the cue, as by riveting or the like.

The collar is further provided with a necked-in grooved portion 13, for a purpose later to be described, and an outer and enlarged disc portion 14 to which a hemispherical or otherwise rounded rubber or other resilient material end 15 may be affixed, said member 15, in the usual construction of billiard cues, being secured to the outer face 12 of the billiard cue. In brief, the spool-shaped adapter is interposed between the outer face of the outer end portion of the cue and the buffer 15 usually affixed thereto, said buffer in the present construction being carried by the spool-shaped adapter rather than the cue end itself.

To the lower longitudinally extending frame member 16' of the billiard rack a plurality of billiard cue socket members 16 are secured, as by wood screws 17 or the like projected through perforations "X" in the base of said socket. Said socket 16 is generally U-shaped in cross section and cylindrical in form having a pair of relatively spaced inturned cylindrical shoulders 18 and 19, the shoulder 18 seating the slightly tapered end 12 of the cue 10 and the shoulder 19 seating the outer edge of the disc 14 of the adapter and restraining further downward movement of the cue in the socket as well as aligning the grooved portion 13 of the spool-shaped adapter with the bore 20 of an outwardly extending sleeve 21, said sleeve being secured within a perforation 22 disposed in the side of said pocket, as best shown in Fig. 5.

The sleeve 21 is also provided with an end cutoff portion 23 adjacent its outermost end, a vertically disposed aperture 24 being provided in the seat 25 thereof, which receives the conventional small padlock P as shown in Fig. 5.

The sleeve 21 is further provided with longitudinally extending slots 26 in opposite sides thereon within which protruding manipulation knobs 28 and 29 of a plunger element 27, telescoped within the sleeve 21, are adapted to ride for reciprocatory forward and rearward movement therein. The plunger 27 is provided with a reduced inner rod end 30 which is adapted to be hand propelled by manipulation of the knobs

28 and 29 into locking and seating engagement within the groove 13.

When the end having the improved adapter of my invention affixed thereto, is inserted within the socket 16, the groove 13 is aligned with the bore of the sleeve 21, the end 30 of the plunger 27 is pushed into seating engagement within the groove, and the padlock shackle or bow 31 is projected through the aperture 24 of the sleeve and then locked by key means K, the shackle 31 thus restraining the plunger from outward movement and locking the cue in the rack. The key K to the padlock is then retained by the owner of the cue. The cue is removed from the rack by a reversal of the above locking movements.

Although my invention has been described in connection with a preferred embodiment, it is to be understood that various and different embodiments might be employed without, however, departing from the spirit of my invention and the scope of the appended claims.

I claim:

1. Locking means for a game stick, having a spool shaped adapter secured to one end of said game stick, said locking means comprising socket means adapted to receive said game stick, said socket means comprising a generally cup-shaped portion and an outwardly extending tubular sleeve portion, a plunger element adapted to be reciprocably mounted within said sleeve portion and adapted to be projected into locking engagement with said spool-shaped adapter end of the game stick, a lock adapted to be associated with

4
said sleeve portion and adapted to prevent outward movement of said plunger means when so projected in locking engagement with the adapter.

5 2. Locking means for a billiard cue, said locking means having grooved means disposed on the outermost end of said cue, said locking means comprising socket means secured to a rack, said socket means having seating means for said 10 grooved end of the cue, said socket means further being apertured, sleeve means mounted within said aperture and projecting laterally of said socket, reciprocably operable means secured within said sleeve and adapted to have reciprocable movement therein, said reciprocably operable means being in alignment with said grooved means when said cue is seated within the said socket, an end of said reciprocably operable means adapted to be projected within said groove, securing means adapted to be projected within the outermost end of the said sleeve to retain said reciprocably operable means in locking engagement with the cue.

JOHN BOWMAN.
